Primary Examiner — Paula Allen Greene(74) *Attorney, Agent, or Firm* — Plumsea Law Group, LLC(57) **CLAIM**

The ornamental design for an illuminated loudspeaker, as shown and described.

DESCRIPTION

The FIGURE is a front view of an illuminated loudspeaker, showing the new design.

The evenly spaced broken lines depict environment that forms no part of the claimed design. The dash-dot broken lines represent the boundaries of the claimed design and form no part of the claimed design.
